ATTORNEY.

UNITED STATES PATENT OFFICE.

ADAM MCKEE, OF UNION, NEW JERSEY.

HOSE-FITTING.

SPECIFICATION forming part of Letters Patent No. 589,216, dated August 31, 1897.

Application filed April 30, 1897. Serial No. 634,542. (No model.)

To all whom it may concern.

Be it known that I, ADAM MCKEE, a citizen of the United States, residing at Union, in the county of Hudson and State of New Jersey, 5 have invented certain new and useful Improvements in Hose-Fittings; and I do declare the following to be a full, clear, and exact description of the invention, such as will enable others skilled in the art to which it appertains to make and use the same, reference being had to the accompanying drawings, and to the letters of reference marked thereon, which form a part of this specification.

The invention relates to improvements in 15 hose-fittings, and pertains particularly to means applicable either to the nozzle or the coupling for the hose, as well as to devices for coupling two pieces of hose together or for mending the hose.

20 The invention pertains particularly to the neck portion of the hose-fitting, which portion enters the hose; and said invention consists in the novel features hereinafter described, and particularly pointed out in the 25 claims.

Referring to the accompanying drawings, forming a part of this application, Figure 1 is a central vertical longitudinal section through a section of hose provided with a coupling 30 constructed in accordance with and embodying the invention, said coupling being also in section. Fig. 2 is a side elevation of a hose-coupling embodying the invention, this coupling being intended for securing two pieces 35 of hose together or for mending the hose and being double-ended or having two corresponding necks, as shown. Fig. 3 is a vertical transverse section on the dotted line 3 3 of Fig. 1, and Fig. 4 is a like section on the dotted line 4 4 of Fig. 1.

In the drawings, referring to Figs. 1, 3, and 4, A designates a section of hose, and B the coupling at the end thereof, said coupling comprising the usual internally-threaded 45 sleeve C and the neck D, which neck embraces the feature comprising the present invention. At one end of the neck D is formed the annular shoulder E, and adjacent to said shoulder E there is formed upon the 50 neck D the annular shoulder F, between which and the annular shoulder G formed on said neck is a broad annular groove H, within

which is placed the sheet-metal band I, snugly filling said groove H and formed from a strip of sheet metal whose ends are correspondingly cut on a diagonal line, as shown at J, and whose entire surface is covered with the prongs K, punched out from the sheet metal and extending outward on inclined lines toward the end of the hose A. The band I is 60 wrapped around the neck D between the annular shoulders F G, and until the neck D has been driven into the hose A the diagonal edges J of said band I will be slightly free of one another, as shown at the left-hand side 65 of Fig. 2, whereas upon the said neck D being driven into the hose the pressure of the latter will bring the said diagonal edges J substantially together, as indicated at the right-hand side of Fig. 2. The inner end of the 70 neck D, beyond the annular shoulder G, is formed with the coarse grooves L, having inclined sides extending outward toward the end of the hose, and upon the inner end of the neck is placed the tight-fitting band M, of 75 rubber or like material, which at its outer edge engages the said shoulder G, the latter acting as a stop for said band M. The band M is of greater thickness than the shoulder G and is of such length that its end projects into 80 the hose beyond the end of the neck D. The purpose of the band M is to prevent leakage around the neck D when the latter is within the hose.

The form of coupling illustrated in Figs. 1, 85 3, and 4 is adapted for connecting the hose to the usual water-supply pipe, the latter being threaded to engage the threaded sleeve C, held upon the neck D by means of the shoulder E at the outer end of said neck. The 90 sleeve C is slipped upon the neck D from the inner end thereof before the band M, and preferably the sheet-metal band E, is applied thereto.

The sheet-metal band I, made from a flat 95 strip, is wrapped around the neck D between the shoulders F G, which act as stops for the ends of the band, and said band I when in position constitutes a snug-fitting sleeve encompassing the neck D, but capable of turning 100 thereon. The band M constitutes an enlarged elongated washer which is prevented from unduly slipping toward the outer end of the neck D by coming into contact with the shoul-

der G and is aided in being retained in position upon the end of the neck D by means of the annular grooves L. When the neck D is forcibly pressed into the end of the hose A, 5 as shown in Fig. 1, the band M will firmly bind against the inner surface of the hose and the external surface of the end of the neck D, and the prongs K of the band I will engage the inner surfaces of the end of the hose and 10 securely retain the latter upon the neck D. There is a substantial advantage in employing the band I having the prongs K in that the prongs will securely engage the hose and the band will permit the hose to turn upon the 15 neck D in instances in which the hose may be twisted prior to the pressure of water being turned into the same. The pressure of the water will frequently be sufficient to force the hose and band I to turn together upon the 20 neck D and thus relieve the hose from its twisted condition.

The form of the invention shown in Fig. 2 is substantially a duplication of the device illustrated in Fig. 1 less the coupling-sleeve 25 C, and the construction shown in Fig. 2 is intended for use in coupling two pieces of hose together—as, for instance, in mending hose or adding a further length thereto.

In Fig. 2 at the center of the coupling is an 30 annular shoulder N, and at each side of this shoulder is provided a neck D corresponding in construction with the neck D of Fig. 1 and the parts of which are lettered correspondingly with the parts of Fig. 1 and require, 35 therefore, no further detailed description. The construction shown in Fig. 2 duplicates the neck D of Fig. 1 in order that the neck at one side of the shoulder N may enter one section of the hose A, while the neck at the other 40 side of the said shoulder N may enter the other section of hose A.

At the right-hand side of Fig. 2 the hose is shown by full lines in position upon the neck D, while at the left-hand side of Fig. 2 the 45 section of hose is indicated by dotted lines and the sheet-metal band I is shown in the condition it has prior to having its edges squeezed together by the pressure of the hose applied thereto. When the neck D of the 50 hose-fitting is forced into the end of the hose, the latter will be rigidly retained thereon and will not require any external wrapping to bind it upon said neck.

What I claim as my invention, and desire 55 to secure by Letters Patent, is—

1. In a hose-fitting, the neck D having the band or washer M at its inner end and pro-

vided with the annular groove H, combined with the band I applied within said groove and having the prongs K inclined outward 60 toward the end of the hose; substantially as set forth.

2. In a hose-fitting, the neck D having at its inner end the grooves L and provided with the annular groove H and shoulders F, G, combined with the band or washer M engaging said grooves L, and the sheet-metal band I applied within said groove H between the shoulders F, G, and having the prongs K struck up therefrom and inclined outward 70 toward the end of the hose; substantially as set forth.

3. In a hose-fitting, the neck D having at its inner end the band or washer M, combined with the sheet-metal band I encompassing 75 said neck and capable of turning thereon, said band having struck-up prongs K inclining outward toward the end of the hose; substantially as set forth.

4. In a hose-fitting, the neck D having the 80 groove H and shoulders F, G, combined with the washer or band M at the inner end of said neck, and the sheet-metal band I applied within said groove H, said band having the diagonal end edges and also the prongs K 85 struck up therefrom and inclining outward toward the end of the hose; substantially as set forth.

5. A hose-fitting having the central annular shoulder N and the necks D at each side of 90 said shoulder, said necks corresponding with one another and each having an annular groove, combined with the washer or band M at the end of each of said necks, the shoulder G at the outer end of each washer or band, 95 and the sheet-metal band I applied within the groove formed between the shoulders N, G, and having the prongs struck up therefrom and inclining outward toward the end of the hose; substantially as set forth. 100

6. In a hose-fitting, the neck D to enter the hose, combined with the sheet-metal band I encompassing and adapted to turn with the hose on said neck, the surface of said band having the series of prongs struck up therefrom and inclining outward toward the end of the hose; substantially as set forth. 105

In testimony whereof I affix my signature in presence of two witnesses.

ADAM MCKEE.
